UNITED STATES PATENT OFFICE.

OTTO WITTEL, OF MOUNT VERNON, NEW YORK, ASSIGNOR TO GENERAL OPTICAL COMPANY, A CORPORATION OF NEW YORK.

LENS-CUTTING MACHINE.

1,406,798.

Specification of Letters Patent. Patented Feb. 14, 1922.

Application filed June 2, 1920. Serial No. 386,035.

To all whom it may concern:

Be it known that I, Otto Wittel, a citizen of the German Republic, residing at Mount Vernon, in the county of Westchester and State of New York, have invented certain new and useful Improvements in Lens-Cutting Machines, of which the following is a full, clear, and exact description.

This invention relates to machines for cutting lenses to the various shapes and sizes required by the optical trade for use with spectacles and eyeglasses.

In the U. S. Patent No. 1,127,860 issued on Feb. 9, 1915, to Hans Clement is disclosed a machine which is readily adjustable for cutting circular, true elliptical or modified elliptical shaped lenses, each of various sizes or proportions without the aid of templets or other gauges for guiding the diamond point.

An object of my invention is to generally improve and simplify the type of machine therein disclosed. More particularly, one of the objects is to improve the lens clamping means and eliminate undesirable strains therein and to lessen the danger of breakage in the cutting operation. Other of the objects are to improve the means used to register the displacement of the diamond point from the center of the lens, and the means for adjusting the device to cut the different shapes of lenses. Another of the objects is to prevent cutting movements of the lens with respect to the diamond in a direction contrary to that for which the diamond is mounted. Another of the objects is to provide means for always maintaining substantially the same angular disposition of the cutting edge of the diamond with respect to the tangent to the outline to be cut at the place of contact, as the lens and diamond are relatively moved to effect the cutting.

Still other objects and advantages will be apparent from the following description and the novel features of my invention will be particularly pointed out in claims.

In the drawings:

Fig. 1 is a side elevation, partly in vertical section, of a cutter which has been constructed in accordance with my invention;

Fig. 2 is a vertical section of the same;

Fig. 3 is a plan of certain of the details;

Fig. 4 is a vertical section taken substantially on the line 4—4 of Fig. 3;

Fig. 5 is a horizontal section taken substantially on the line 5—5 of Fig. 1; 55

Fig. 6 is a plan of the illustrated cutter;

Fig. 7 is a horizontal section taken substantially on the line 7—7 of Fig. 1 with the parts in one relative position; 60

Fig. 8 is a section along the line 7—7 of Fig. 1 but with the parts in a relative position different from that illustrated in Fig. 7; and

Fig. 9 is a section taken substantially 65 along the line 9—9 of Fig. 6 and illustrating automatic diamond shifting means.

In the illustrated embodiment, the main frame or standard 1 has a suitable base 2 and two lateral extensions 3 and 4. The extension 3 is provided with a vertically extending passage or aperture 5 which is provided with screw threads 6 for a short distance down from the upper bearing face 7 of the extension. Within the threaded portion of the aperture 5 is a hollow lock nut 8 which is adjustable up and down in the recess to act as a locking stop for the end of a hollow stem 9 which is adjustably threaded into and out of the aperture in co-operation with the threads 6. A gear member 10 is rotatably carried upon the stem 9 and held against the bearing face 7 of the extension by means of a shoulder 11 of the stem. Adjustment of the stem into or out of the aperture will 85 thus enable the elimination of lost motion or binding between the gear member and the bearing surface 7 of the extension. Upon the upper face of the gear member 10 may provide a steel plate 12 to take up wear if 90 the gear member 10 is of soft material. A member 13 is slidable upon the plate 12 (or gear member 10 if the wear plate is omitted) and is held upon the plate or gear member by another shoulder or head 14 of the stem 95 9, the shank of the stem passing through an elongated slot 15 in the bottom wall of the member 13. Excessive sliding movement of the member 13 upon the plate or gear member is prevented by the engagement of the 100 ends of the slot with the stem. A hollow cap 16 is threaded to an upstanding annular flange 17 of the member 13 to form with the latter a hollow drum.

The cap 16 has an extension 18, from the 105 upper end of which projects a bearing stud 19 having a ball or spherically shaped end, the stud being removably held in a recess 20

of the extension by a set screw 21. A lens supporting table 22 has a somewhat spherically shaped recess in its under side for the reception of said ball-shaped stud 19 which permits of a limited universal rocking movement of the table. The table 22 is provided with a vertically extending transverse slot 23, leading outwardly from the spherically shaped recess. A pin 24 projects 10 radially and horizontally from one side of the ball-shaped bearing stud into said slot 23 in order to cause rotation together of the table and extension 18 without interfering with the universal connection between them. 15 Thus the table can rock and conform to the position of the complementary clamping member without producing excessive stresses in any portion of the lens. Secured to the upper face of the table is an indicating or 20 reference disc 25, preferably elliptical, and having indicated thereon, perpendicular axes intersecting the axis of the table. A resilient annular washer 26 is secured to the upper face of disc 25 substantially concentric with the intersecting axes. The stud 25 19 is provided with a vertical passage 27 the lower end of which is enlarged as shown. A pin 28 is inserted into this passage through the lower end of the latter, upward movement of the pin being limited by the engagement of an enlarged head 29 of the pin 28 with the shoulder formed at the change in size of the passage. A spring 30 reacts between the extension 18 and the head 29 to 35 yieldingly hold the pin in its upper positions.

A sleeve 31 is slidable within the stem 9 being limited in its downward movement by the engagement of an enlarged head 32 with an internal shoulder 33 of the stem. A plate 34 is provided with an elongated slot or aperture 35 through which passes a non-circular boss 36 having parallel sides upon the upper end of the sleeve 31, the plate resting 40 and sliding upon the upper ends of the stem and sleeve. The parallel sides of this boss fit the sides of the slot and prevent rotation of the plate upon the sleeve. An annular cam ring 37 is secured to the periphery of 45 the plate 34 in any suitable manner such as by screws 38 threaded into the two parts between abutting surfaces. The cam ring is provided upon its periphery with a plurality of cam surfaces 39 and 40 in different 50 horizontal planes, that is spaced vertically apart. These cam surfaces co-operate selectively with a pair of cam followers or guides 41 which project inwardly from the upstanding portion 17 of the plate 13, and 55 which are arranged at opposite ends of the elongated slot 15. As the sleeve 31 is shifted vertically in the stem, the plate 34 and the cam ring will be simultaneously shifted to bring the cam surfaces 39 and 40 selectively 60 into co-operative relation with the

guides. Thus when the gear member 10 and plate 13 are rotated, the guides 41 will move around the cam surface with which it is in engagement and the plate 13 and cap 16 will be simultaneously given a lateral movement which is dependent in character upon the contour or periphery of the cam surface then in contact with the guides. In order to permit the lateral movement described, and yet cause rotation of the plate 13 with the gear member, the latter is provided upon its upper face with a roller pin or a lug 42 which is received in a short elongated radial slot or recess 43 in the under face of the plate 13. An anti-friction roller 44 may be 65 provided adjacent the under face of the plate 13 for rolling engagement with the upper face of the gear member 10 or wear plate 12, the roller being arranged with its axis radially of the plate 13 and upon the side opposite from the slot 43. A rod 45 is rotatably carried within the sleeve 31 and is provided at its upper end with a cam disc 46 arranged eccentric to the axis of the rod and overlapping the plate 34 to hold the 70 same upon the sleeve 31. The cam disc 46 co-operates with oppositely disposed guides 47 and 48 upon the plate 34, whereby upon rotation of the rod 45, the disc will act as a crank and be rotated eccentrically and 75 shift plate 34 laterally or eccentrically to the axis of shaft 45. The slot 35 in the plate 34 confines the plate to a reciprocating movement upon the sleeve and a pin 34^a projecting from the plate 34 contacts with 80 the edges of the cam disc 46 to limit rotation of the latter and rod 45 to one-half a rotation. The cam ring 37 moves with the plate 34 and thus is shifted laterally to a position eccentric to the axis of rotation of the 85 gear member 10. If now the gear member 10 is rotated, the plate 13 and cap 16 will be given an oscillatory and lateral sliding movement as the guides 41 follow the cam surface with which it engages, dependent 90 in extent upon the extent of displacement of the cam ring from the axis of rotation. The cam surfaces also modify this movement in accordance with the nature of their 95 surface.

ing it forms an extension of the sleeve and holds the latter against withdrawal, and the bushing acts as a lock nut for locking the head to the sleeve. An operating button 54 is fixedly secured to the end of the rod 45 and against the head 53 by a set screw 55 and a nut 56. When the button 54 is rotated, the rod or shaft 45 will be rotated and the cam disc 46 shifted to vary the degree of eccentricity or lateral displacement of the cam ring, and when the button is shifted endwise, that is, vertically, the rod 45 and sleeve 31 will be shifted endwise and carry the cam ring 37 upwardly to dis-
engage the cam surface 39 from the guides and place the cam surface 40 in engagement with the guides. The cam surfaces can be shifted at will by endwise movement of the button and the eccentricity or lateral dis-
placement of the cam ring varied at will by rotation of the button. In the lower end of the head 53 I provide recesses 57 in which detents 58 are slidable, being yieldingly pressed outwardly by springs 59 in the re-
cesses which react between the head and detents. The detents engage in depressions 60 in the button and assist in determining the various adjustments, as well as yieldingly hold the button in any adjusted po-
sitions. The depressions 60 may be readily provided by securing a disc 61, having ap-
ertures therein and constituting the depressions, to that face of the button which abuts the head 53. The apertures are so arranged
that when one detent is in engagement with a depression 60, the other detent is between depressions adjacent to it, and vice versa. This arrangement enables the placing and holding of the button in very close suc-
cessive positions. The peripheral flange 62 of the button embraces the head and sleeve device with provision for the necessary sliding movement of the sleeve, and is provided along its edge with graduations which co-
operate with reference points upon the sleeve device to indicate the successive vertical po-
sitions of the cam ring and the extent of the displacement of the ring laterally and eccentrically to the axis of the sleeve. These graduations and reference points are illus-
trated in Fig. 2.

A bearing stud 63 is threaded into an aperture in one wall of the extension 3, the aperture communicating with the vertical passage 5. A gear 64 is rotatably carried by the stud and meshes with the gear mem-
ber 10 to drive the same. The gear 64 is held upon the stud 63 by the head 65 of the latter, and the stud is adjustable into and out of the extension to take up lost motion between the gear and the extension or head. A suitable ball or roller one way clutch 64^a is provided between the gear 64 and extension 3 to limit rotation of the gear
to one direction. The details of such

clutches are well known and a detailed de-
scription is believed to be unnecessary. The inner end of the stud is provided with a recess 66 which communicates with the aperture or vertical passage 5. A detent 67 is 70
slidable in the open end of the recess and a spring 68 reacting between the closed end of the recess and the detent tends to normally eject the detent from the recess. The detent engages upon the periphery of the 75 sleeve 31 and is adapted to enter alternately recesses or notches 69 in the sleeve and yieldingly hold the sleeve in vertically adjusted positions. A crank arm 70 or other equiva-
lent means is used to rotate the gear 64, pro-
vision must be made for clamping the lens to the table and the clamping means must be able to follow the lens in its path of movement without breaking or unduly straining the lens, or imposing too great a 80
load upon the operating means. Accord-
ingly I provide a vertically extending aper-
ture 71 in the extension 4 which is in align-
ment with the aperture 5 of the extension 3. A sleeve 72 is slidable in said aperture 90
and has a slot 73 in its upper end into which projects a depending flange of the clutch handle 74. The handle is pivotally mount-
ed on the frame 1 at 75 and a spring 76
reacting between the frame and handle tends 95
constantly to raise the handle to an un-
clamped position. The handle carries a
spring pressed latch 77 which automatically
latches over catch 78 upon the extension 4
when the handle is depressed to clamp a 100
lens upon the table. A spring 79 within the
sleeve 72 reacts between the latter and the
handle to yieldingly force the sleeve down-
wardly when the handle is depressed. The
latch 77 has a plurality of teeth thereon so 105
that it can be latched in selected positions
and thus provide different degrees of pres-
sure upon the sleeve and through it upon
the lens. The sleeve is provided at its lower
end with a bearing surface 80 across which 110
the balls or rollers 81 carried by the hold-
ing plate or ring 82 roll. A clamping frame
or member 83 comprises two annular rings
spaced by studs 84, the upper annular ring
having a bearing surface 85 which abuts 115
against the rollers or balls 81. The mem-
ber 83 and ring 82 have frusto-conical cen-
tral apertures therein in which is disposed
a cone-shaped aligning member 86. The
member 86 is pivotally attached to one end 120
of a resilient element 87 which extends
through the apertures in the member 83,
ring 82, the sleeve 72 and spring 79 and is
pivotally connected at its other end to the
handle 74. When the handle is depressed 125
to clamp a lens upon the table, the member
86 is lowered slightly from the frusto-coni-
cal apertures in member 83 and ring 82, so
as to permit of limited lateral movement of
these parts upon the bearing surface 80. 130

When the handle is unlatched the spring lifts it and through the resilient element 87 also the cone-shaped aligning element, the latter by its camming action with the walls 5 of the apertures in member 83, ring 82 and the hollow sleeve 72 centering or aligning these members and holding them together above the lens table. The lower ring 88 of the member 83 is provided with a resilient 10 ring or gasket 89 for gripping the lens when in contact therewith.

The frame 1 is provided intermediate of its height with a horizontally extending aperture 90 in one end of which is slidably but 15 non-rotatably carried a sleeve element 91. An operating button 92 is threaded into the other end of the aperture and has an extension 93 provided with screw threads extending in a direction opposite from those 20 between the button 92 and the aperture in the frame. The sleeve element 91 is provided with internal screw threads adjacent its inner end into which the extension 93 is threaded. As the button 92 is rotated to move it into or out of the aperture the extension 93 will also rotate, and since the sleeve element 91 cannot rotate, it will be shifted along the aperture and relatively to the extension 93, in addition to its movement 25 along the aperture which it receives by the travel of the button and extension relative to the aperture. The sleeve element therefore receives from the button an amplified movement in the same direction as that of the button. The button 92 may be threaded 30 directly into the frame 1 or into a sleeve like extension as shown. The button is provided upon its periphery with spirally arranged graduations which co-operate with 35 a reference point 92^b upon the frame to indicate the displacement of the sleeve element 91 and the parts carried by it. In the outer closed end of the sleeve element 91 is rotatably carried a small pivot 94 held 40 therein by a flange 95 at one end which abuts against the end wall and a long bolt 96 which is threaded into the other end, the bolt having a shoulder 97 which forces a washer 98 against the inside of the end wall 45 of the sleeve element 91. The bolt extends through a central aperture in the button 92 and extension 93 and has an enlarged head 99 forming an internal bearing for the button. The sleeve element 91 and button 92 50 thus have a rather long bearing axis which prevents binding of the parts.

The pivot 94 has integral therewith an operating arm 100 having a split end 101 in which is pivotally held an extension arm 60 102, the latter being held against detachment therefrom by a screw 103 in the arm 100 which extends into an annular groove 104 therein. A screw 105 extending between the parts of the split end 101 enables the 65 clamping of the extension arm 102 to any

desired extent so as to hold it frictionally in any adjusted position about the axis of the extension arm. A finger engaging button 106 is provided upon the extension arm 102 for rotating the same. A cutting tool 107 70 is rotatably mounted in the free end of the extension arm with its cutting tip in alignment with the axis of extension arm 102 and has a crank arm 108 attached thereto, the latter having a slot 109 therein. A 75 forked arm 110 is pivoted to the extension arm by pivot 110^a and carries a pin 111 which engages in the slot 109 in the arm 108. The forked arm embraces the extension or neck 18 of the lens supporting means and as the latter moves elliptically or non-circularly it oscillates the forked arm and through the pin 111 and slot 109 oscillates the cutter 107 to always present it to the lens with substantially the same angular disposition of the cutting edge of the diamond with respect to the tangent to the outline to be cut at the place of contact.

The operation is similar to that of the machine disclosed in the patent referred to, but 90 will be briefly described. A lens is placed upon the resilient ring 26 of the table 22 with its optical center directly over the pin 28, and with the major and minor axes (if a non-circular lens is to be cut) in alignment 95 with the indicated axes of the disc 25. The handle 74 is now depressed to compress the spring 79 and force the gasket or washer 89 against the upper face of the lens and hold it firmly upon the table. The holding force 100 can be varied by latching any one of the teeth of the latch 77 over the catch 78. The cone member 86 drops down during the latching operation so as to permit of the requisite lateral movement of the clamping 105 element 83 and the ball holder 82. The button 92 is turned to displace the sleeve element 91 and through it displace the cutter 107 the desired distance from the normal center of rotation of the lens or the gear 110 member 10, which distance will be indicated by the spiral scale 92^a and reference point 92^b. As the button 92 moves into and out of the aperture of the frame during its rotation, the spiral scale always has a portion 115 adjacent the reference point 92^b for proper and accurate reading. If a circular lens is to be cut, the sleeve is shifted to its lower position by button 54, to bring the cam surface 39 into co-operative contact with the 120 guides 41, and the button 54 is rotated to the position indicated in Fig. 2 to bring the cam ring into the position indicated in Fig. 7, that is, concentric to the axis of rotation. Crank arm 70 is now rotated, which causes 125 rotation of gear member 10 and the lens support. The cam surface 39 is circular so that the lens will be given a circular or rotary movement. The button 106 is operated to present the cutter 107 radially to 130

the under side of the lens and then arm 100 is depressed which shifts the cutter into contact with the lens and cuts the latter as it rotates. To remove the lens, the handle 5 74 is slightly depressed and unlatched, spring 76 then promptly lifts the handle and clamping means clear of the lens, and as the handle moves upwardly, the cone shaped member 86 aligns the clamping 10 means with the sleeve 72.

If a true elliptical lens is to be cut, the blank is clamped upon the table in the same manner with its major and minor axes over the corresponding axes of the disc 25, the 15 button 54 shifted to its lower position if not already there, and then rotated to shift cam ring eccentrically to the axis of rotation to the desired extent. The scale upon the button will indicate to the operator the extent 20 of eccentricity to which the instrument has been adjusted. This adjustment determines the major axis of the ellipse. The button 92 is next adjusted to displace the cutter the proper distance from the axis of normal 25 rotation which will determine the minor axis of the ellipse. The crank handle 70 may now be operated to rotate the lens and the arm 100 depressed which will bring the cutter into contact with the lens to cut the 30 same. Of course the handle 106 will in any case be first shifted so as to present the cutter radially to the lens. In Fig. 8 the maximum displacement of the cam ring from the center of rotation is illustrated. 35 The cam disc 46 may assume any position intermediate the positions indicated in Figs. 7 and 8 upon proper adjustment of button 54, so that any desired proportion of the axes of the ellipse can be obtained. As the 40 lens is eccentrically rotated, the forked arm 110 will be oscillated and the cutter 107 oscillated about its own axis so that the cutting edge will always be similarly presented to the cutting line of the lens under the various 45 elliptical proportions of the lenses being cut, that is, so as to have always substantially the same angle with respect to the tangent to the cutting line at the place of contact, which prevents injury to the cutting 50 edge. The clutch between the gear and extension prevents movement between the lens and diamond cutter in a direction different from that for which it was mounted. Danger of injury to the diamond from cutting 55 in the wrong direction is therefore eliminated.

If a modified elliptical lens such as those intended for use with rimless or frameless glasses is to be cut, the buttons 54 and 92 are 60 set as for a true elliptical lens in proportioning the axes. The button 54 is however shifted upwardly into the position marked "frameless" (Fig. 2) to simultaneously shift the sleeve 31 into its upper position and 65 thus disengage the cam surface 39 of the rim

ring from engagement with the guides 41 and engage the cam surface 40 therewith instead. During this movement the detent 67 is automatically snapped out of one depression 69 and into the other to hold the 70 sleeve in the adjusted position. Upon rotation of the lens it will not only be given the general elliptical movement, but the cam surface 40 will modify this movement in the manner desired. That is, the cam surface 75 40 has four high spots spaced around its periphery. The high spots of the cam surface modify the movement to provide an ellipse with its ends filled out or oval shaped and not exactly truly elliptical. By varying 80 the shape of the cam surface 40 the exact shape of the lens can be accordingly varied. It is obvious that various changes in the details of construction herein described and illustrated may be made within the principle 85 and scope of my invention.

I claim:

1. In a lens cutting machine, a frame, a lens table, means for supporting the table upon the frame and for imparting thereto a 90 rotary movement and simultaneously also a prescribed movement within its plane, and clamping means carried by the frame comprising two sections, one of which is movable upon the other and in contact with the 95 lens when the clamping means is effective.

2. In a lens cutting machine, a frame, a lens table, means for supporting the table upon the frame and for imparting thereto a rotary movement and simultaneously also 100 a prescribed movement within its plane, clamping means carried by the frame comprising two sections, one of which is movable upon the other and in contact with the lens when the clamping means is effective and 105 an anti-friction bearing between the two sections.

3. In a lens cutting machine, a frame, a lens table, means for supporting the table upon the frame and for imparting thereto 110 a rotary movement and simultaneously also a prescribed movement within its plane, a sleeve having a bearing surface carried by said frame for movement toward or from the table with the bearing surface parallel 115 to the table, a clamping member, an anti-friction bearing device between the member and bearing surface, and means operable when in one position for yieldingly holding said member against the lens upon the table 120 and when in another position for withdrawing the sleeve and member from the lens, said means being effective to center the member with respect to the sleeve and hold the member in the said centered position when 125 the latter is out of contact with a lens and permit lateral movement of the member when it is in contact with a lens.

4. In a lens cutting machine, a frame, a lens table, means for supporting the table 130

upon the frame and for imparting thereto a rotary movement and simultaneously also a prescribed movement within its plane, clamping means carried by the frame comprising two sections, one of which is movable upon the other and in contact with the lens when the clamping means is effective, an anti-friction bearing between the two sections, and means for centering the movable section with respect to the relatively fixed section when the clamping means is ineffective and for permitting movement of one section upon the other when the clamping means is effective.

15 5. In a lens cutting machine, a rigid supporting frame, a lens table, means for supporting the table upon the frame and for imparting thereto a combined rotary and lateral movement, and clamping means directly carried by the frame for releasably holding a lens upon the table and permitting movement of the same with the table.

20

6. In a lens cutting machine, a rigid supporting frame, a lens table, means for supporting the table upon the frame and for imparting thereto a combined rotary and lateral movement, a sleeve carried by the frame for movement toward or from the table and having a bearing surface upon its lower end, a clamping member, an anti-friction device between the member and surface, means for yieldingly depressing said sleeve and member toward the table for clamping a lens thereon, and a centering device connected to said means for centering said member and anti-friction device with respect to the sleeve and holding them so centered when the clamping member is out of contact with a lens upon the table, and for releasing them for relative movement when the member is in contact with a lens.

7. In a lens cutting machine, a rigid supporting frame, a lens table, means for supporting the table upon the frame and for imparting thereto a combined rotary and lateral movement, a sleeve carried by the frame for movement toward or from the table and having a bearing surface upon its lower end, a clamping member, an anti-friction device between the member and surface, a handle pivoted to the frame and extending over the sleeve, a spring tending to retract said handle from the sleeve, a spring reacting between the sleeve and handle, and a

55 *centering device connected to the handle and passing through the member, anti-friction device and sleeve, and having a resilient portion, whereby when the handle is free it lifts the member, anti-friction device and*

60 *sleeve from the table and centers the member and antifriction device with respect to the sleeve, and when the handle is depressed to clamp a lens upon the table it releases the antifriction device and member to permit*

lateral and rotary movement of the same 65 with the lens and table.

8. In a lens cutting machine, a rigid supporting frame, a lens table, means for supporting the table upon the frame and for imparting thereto a combined rotary and lateral movement, a sleeve carried by the frame for movement toward or from the table and having a bearing surface upon its lower end, a clamping member, an anti-friction device between the member and surface, a handle pivoted to the frame and extending over the sleeve, a spring tending to retract said handle from the sleeve, a spring reacting between the sleeve and handle, and a centering device connected to the handle and passing through the member, anti-friction device and sleeve whereby when the handle is free it lifts the member, anti-friction device and sleeve from the table and centers the member and antifriction device with respect to the sleeve, and when the handle is depressed to clamp a lens upon the table it releases the antifriction device and member to permit lateral and rotary movement of the same with the lens and table. 70 75 80 85 90

9. In a lens cutting machine, a rigid supporting frame, a lens table, means for supporting the table upon the frame and for imparting thereto a combined rotary and lateral movement, a sleeve carried by the frame for movement toward or from the table and having a bearing surface upon its lower end, a clamping member, an anti-friction device between the member and surface, a handle pivoted to the frame and extending over the sleeve, a spring tending to retract said handle from the sleeve, a spring reacting between the sleeve and handle, a centering device connected to the handle and passing through the member, anti-friction device and sleeve whereby when the handle is free it lifts the member, anti-friction device and sleeve from the table and centers the member and anti-friction device with respect to the sleeve, and when the handle is depressed to clamp a lens upon the table it releases the anti-friction device and member to permit lateral and rotary movement of the same with the lens and table, and means for latching the handle in clamping position. 115

10. In a lens cutting machine, a frame, a table, a spindle having a universal connection to said table, means for mounting said spindle upon the frame and for imparting thereto a combined rotary and lateral movement, and means for clamping a lens to said table. 120

11. In a lens cutting machine, a spindle 125 having a ball-shaped end, a table having a socket therein for receiving the ball-shaped end upon which it is supported for a limited

universal rocking movement, a pin projecting radially from one side of the ball and perpendicularly to the axis of the table, said table having a slot in the vertical plane of 5 the pin for causing rotation together of the table and spindle.

12. In a lens cutting machine, a frame, a stem on said frame, a plate rotatably carried by the stem, means for rotating the 10 plate about said stem, a drum carried by the stem in contact with said plate and having a slot therein through which the stem passes, said plate and drum having co-operating means for causing rotation together and permitting 15 a limited lateral sliding movement of the drum upon the plate, a lens table carried by the drum, a pair of guides upon diametrically opposite sides of said drum at the ends of the slot, a non-rotatable cam between 20 the guides and having a plurality of differently shaped cam surfaces around its periphery, and means for shifting said cam to alternatively bring any one of the cam surfaces into engagement with the guides.

25 13. In a lens cutting machine, a frame, a stem on said frame, a plate rotatably carried by the stem, means for rotating the plate about said stem, a drum carried by the stem in contact with said plate and having a slot 30 therein through which the stem passes, said plate and drum having co-operating means for causing rotation together and permitting a limited lateral sliding movement of the drum upon the plate, a lens table carried by the drum, a pair of guides upon diametrically opposite sides of said drum at the ends of the slot, a non-rotatable cam between 35 the guides and having a plurality of differently shaped cam surfaces around its periphery, means for shifting said cam to bring alternatively any one of the cam surfaces into engagement with the guides and means for selectively displacing said cam eccentrically to the axis of rotation 40 of the plate.

45 14. In a lens cutting machine, a frame, a hollow stem on said frame, a plate rotatably carried by the stem, a drum carried by the stem and connected to the plate for rotation therewith and lateral movement thereon, a lens support carried by the drum, diametrically opposed guides in said drum, a sleeve extending through and slidable in said hollow stem, a cam member carried by the sleeve between the guides and having a plurality of different cam surfaces between the guides adjustable selectively into engagement with the guides upon sliding movement of the sleeve in the stem, and means for 50 at will displacing the cam member eccentrically with respect to the axis of rotation of the plate.

55 15. In a lens cutting machine, a frame, a hollow stem on said frame, a plate rotatably carried by the stem, a drum carried by the

stem and connected to the plate for rotation therewith and lateral movement thereon, a lens support carried by the drum, diametrically opposed guides in said drum, a sleeve extending through and slidable in said hollow stem, a cam member carried by the sleeve between the guides and having a plurality of different cam surfaces between the guides adjustable selectively into engagement with the guides upon sliding movement of the sleeve in the stem, a rod extending through the sleeve, a cam disc carried by said rod within the cam member, guides on said cam member on opposite sides of the cam disc whereby rotation of the rod will 70 through the action of the cam disc upon the guides of the cam member shift the latter eccentrically with respect to said rod.

75 16. In a lens cutting machine, a frame, a hollow stem on said frame, a plate rotatably carried by the stem, a lens support having a slot through which the stem passes, said support being held upon the plate by said stem and having connection with the plate to cause rotation together and simultaneously 80 permit movement of the support along the slot and upon the plate, guides carried by the support, and a cam device having a plurality of cam surfaces thereon and adjustable vertically to bring any selected cam surface into co-operative relation with the guides.

85 17. In a lens cutting machine, a frame, a hollow stem on said frame, a plate rotatably carried by the stem, a lens support having a slot through which the stem passes, said support being held upon the plate by said stem and having a connection with the plate to cause rotation together and simultaneously 90 permit movement of the support along the slot and upon the plate, guides carried by the support, a cam device having a plurality of cam surfaces thereon and adjustable vertically to bring any selected cam surface into co-operative relation with the 95 guides and means for displacing said cam member eccentrically with respect to the axis of rotation of the plate.

100 18. In a lens cutting machine, a hollow stem on said frame, a plate rotatably carried by the stem, a lens support having a slot through which the stem passes, said support being held upon the plate by said stem and having a connection with the plate to cause rotation together and simultaneously 105 permit movement of the support along the slot and upon the plate, guides carried by the support, a sleeve passing through the stem, a cam member carried by the sleeve and slidable laterally thereon, said cam member having a plurality of cam surfaces thereon, means for adjusting said sleeve endwise to bring any selected cam surface into co-operative engagement with the guides and to yieldingly retain the sleeve in adjusted positions, 110 115 120 125 130

and means for displacing said cam member eccentrically to said sleeve.

19. In a lens cutting machine, a frame, a hollow stem on said frame, a plate rotatably carried by the stem, a lens support having a slot through which the stem passes, said support being held upon the plate by said stem and having a connection with the plate to cause rotation together and simultaneously permit movement of the support along the slot and upon the plate, guides carried by the support, a sleeve passing through the stem, a cam member carried by the sleeve and slidably laterally thereon, said cam member having a plurality of cam surfaces thereon, means for adjusting said sleeve endwise to bring any selected cam surface into co-operative engagement with the guides and to yieldingly retain the sleeve in adjusted positions, guides on said cam member, a rod extending lengthwise through said sleeve, a cam disc eccentrically carried upon the upper end of the rod and between the guides of the cam member whereby rotation of the rod displaces the cam member eccentrically of the sleeve.

20. In a lens cutting machine, a frame, a lens support, means carried by the frame for giving said support a combined rotary and lateral movement, and controlling means adjustable in a rotary direction to vary the extent of the lateral movement and in an endwise direction to also produce a modified lateral movement of substantially the same extent.

21. In a lens cutting machine, a frame, a lens support, means carried by the frame for giving said support a combined rotary and lateral movement, controlling means including an operating member adjustable in a rotary direction to vary the extent of the lateral movement and in an endwise direction to also produce a modified lateral movement of substantially the same extent, and means for yieldingly retaining said controlling means in adjusted positions in both directions.

22. In a lens cutting machine, a frame, a hollow stem on said frame, a plate rotatably carried by the stem, a lens support having a slot through which the stem passes, said support being held upon the plate by said stem and having a connection with the plate to cause rotation together and simultaneously permit movement of the support along the slot and upon the plate, guides carried by the support, a cam device having a plurality of cam surfaces thereon and adjustable vertically to bring any selected cam surface into co-operative relation with the guides and a detent device for retaining the cam device in adjusted positions.

23. In a lens cutting machine, a frame, having a horizontal extension, a stem projecting upwardly from the extension, lens support-

ing and rotating means carried by the stem, means including a sleeve slidably in said stem and extension for varying the path of movement of the lens supporting means, a bearing boss extending horizontally from said extension, a spring pressed detent slidably in said boss and engageable with said sleeve for holding it in adjusted position, and means carried by the boss for imparting movement to the lens supporting and rotating means.

24. In a lens cutting machine, a frame having a horizontal extension, said extension having a vertical passage therethrough, lens supporting and rotating means carried by the extension, a device for controlling the movement of the said means and including a member slidable in said vertical passage, a horizontal bearing boss carried by said extension and having a recess therein connecting with said vertical passage, a detent slidably in said recess and engaging with said sleeve to hold the latter in adjusted positions, a spring in said recess for yieldingly pressing said detent against the sleeve, and means carried by the boss for imparting movement to the lens supporting and rotating means.

25. In a lens cutting machine, a frame having an extension, lens supporting and rotating means carried by the extension, controlling devices for said means, a sleeve slidably in said extension and carrying one of said controlling devices, a rod rotatable within said sleeve and carrying the other of said devices and an operating button on said rod and embracing said sleeve whereby said button can be operated to slide the sleeve and control one device and to rotate the rod and control the other device.

26. In a lens cutting machine, a frame having an extension, lens supporting and rotating means carried by the extension, controlling devices for said means, a sleeve slidably in said extension and carrying one of said controlling devices, a rod rotatable within said sleeve and carrying the other of said devices, an operating button on said rod and embracing said sleeve whereby said button can be operated to slide the sleeve and control one device and to rotate the rod and control the other device, said button having on its inner face a plurality of spaced recesses, and a spring pressed detent carried by the sleeve and engageable in said recesses upon rotation of the button and rod to accurately position the rod and hold the same in adjusted positions.

27. In a lens cutting machine, a frame having an extension, lens supporting and rotating means carried by the extension, controlling devices for said means, a sleeve slidably in said extension and carrying one of said controlling devices, a rod rotatable within said sleeve and carrying the other of

said devices, an operating button on said rod and embracing said sleeve, whereby said button can be operated to slide the sleeve and control one device and to rotate the rod and 5 control the other device, said button having on its inner face a plurality of rows of spaced recesses, and spring pressed detents carried by the sleeve and engageable alternately in said recesses upon rotation of the 10 button and rod to accurately position the rod and hold the same in adjusted positions.

28. In a lens cutting machine, a frame having lateral and vertical extensions, lens supporting means rotatably carried by the 15 lateral extension, lens clamping means carried by the vertical extension, a bearing boss extending from said lateral extension, a gear member rotatably carried by the boss, means for rotating said gear member, and a 20 one way clutch between the gear and extension, for permitting movement of the gear in but one direction.

29. In a lens cutting machine, a frame having lateral and vertical extensions, lens 25 supporting means rotatably carried by the lateral extension, lens clamping means carried by the vertical extension, a bearing boss extending from said lateral extension, a gear member rotatably carried by the boss, means 30 for rotating said gear member, and a roller clutch between a face of the gear member and the extension for permitting movement of the gear in but one direction.

30. In a lens cutting machine, a frame 35 having a horizontal extension, said extension having a vertical passage therethrough, lens supporting and rotating means carried by the extension, a device for controlling the movement of the said means and including a member slidable in said vertical passage, a horizontal bearing boss carried by said extension and having a recess therein connecting with said vertical passage, a detent 40 slidable in said recess and engaging with said sleeve to hold the latter in adjusted positions, a spring in said recess for yieldingly pressing said detent against the sleeve, a gear member rotatably carried by the boss and connected to the lens supporting 45 and rotating means for imparting movement thereto, means for rotating the gear member, and a one way clutch between the face of the gear member and extension for limiting rotation of the gear to one direction.

31. In a lens cutting machine, a frame having a horizontal extension, said extension having a vertical passage therethrough, a lens supporting and rotating means carried 50 by the extension, a device for controlling the movement of the said means and including a member slidable in said vertical passage, a horizontal bearing boss carried by said extension and having a recess therein connecting with said vertical passage, a de-

tent slidable in said recess and engaging with said sleeve to hold the latter in adjusted positions, a spring in said recess for yieldingly pressing said detent against the sleeve, a gear member rotatably carried by 70 the boss and connected to the lens supporting and rotating means for imparting movement thereto, means for rotating the gear member, and means for limiting rotation of the gear member to one direction. 75

32. In a lens cutting machine, a frame having a vertically extending aperture and a bearing face upon the frame at the upper end of the aperture, a hollow stem adjustably threaded into the upper end of said aperture and having stepped shoulders upon its upper end, a hollow lock nut adjustably threaded into the aperture for limiting the inward movement of the stem, a gear rotatably carried by the stem and held against 80 the upper bearing surface of the frame by the smaller shoulder, a lens support having an elongated slot in its lower face through which the portion of the stem between the shoulders passes, said support being held 85 against the gear by the larger shoulder, but slideable across the same by means of the slot, a sleeve slideable vertically in said stem, a plurality of cams carried by the upper end of the sleeve and co-acting with the support to selectively control its path of movement, dependent upon the extent of vertical adjustment, means including a gear member meshing with said gear for rotating the gear and support, and means for vertically shifting and holding in shifted positions said sleeve and cams. 90

33. In a lens cutting machine, a frame having a vertically extending aperture and a bearing face upon the frame at the upper 100 end of the aperture, a hollow stem adjustably threaded into the upper end of said aperture and having stepped shoulders upon its upper end, a gear rotatably carried by the stem and held against the upper bearing 105 surface of the frame by the smaller shoulder, a lens support having an elongated slot in its lower face through which the portion of the stem between the shoulders passes, said support being held against the gear by the larger shoulder, but slideable across the same by means of the slot, a sleeve slideable vertically in said stem, a plurality of cams carried by the upper end of the sleeve and co-acting with the support to selectively control its path of movement, dependent upon the extent of vertical adjustment, means including a gear member meshing with said gear for rotating the gear and support, and means for vertically shifting said sleeve and 115 cams. 120

34. In a lens cutting machine, a frame having a vertically extending aperture and a bearing face upon the frame at the upper end of the aperture, a hollow stem adjustably 130

- threaded into the upper end of said aperture and having stepped shoulders upon its upper end, a gear rotatably carried by the stem and held against the upper bearing surface 5 of the frame by the smaller shoulder, a lens support having an elongated slot in its lower face through which the portion of the stem between the shoulders passes, said support being held against the gear by the larger 10 shoulder, but slidable across the same by means of the slot, a sleeve slidable vertically in said stem a plurality of cams carried by the upper end of the sleeve and co-acting with the support to selectively control its 15 path of movement, dependent upon the extent of vertical adjustment, means including a gear member meshing with said gear for rotating the gear and support, a rod rotatably carried by the stem, means carried by 20 the upper end of the rod for displacing the cams upon the sleeve to various extents eccentrically to the axis of rotation of the gear and an operating button upon the lower end of the rod for rotating the same to vary the 25 eccentricity of the cams and abutting the sleeve to shift the same to change the cams in control of the support when the button and rod are shifted endwise.
35. In a lens cutting machine, a frame 80 having a vertically extending aperture and a bearing face upon the frame at the upper end of the aperture, a hollow stem adjustably threaded into the upper end of said aperture and having stepped shoulders upon 85 its upper end, a gear rotatably carried by the stem and held against the upper bearing surface of the frame by the smaller shoulder, a lens support having an elongated slot in its lower face through which the portion of the 90 stem between the shoulders passes, said support being held against the gear by the larger shoulder, but slidable across the same by means of the slot, a sleeve slidable vertically in said stem, a plurality of cams carried by 95 the upper end of the sleeve and co-acting with the support to selectively control its path of movement, dependent upon the extent of vertical adjustment, means including a gear member meshing with said gear for 100 rotating the gear and support, a rod rotatably carried by the stem, means carried by the upper end of the rod for displacing the cams upon the sleeve to various extents eccentrically to the axis of rotation of the gear, a hollow sleeve rigidly carried by the frame at the lower end of the aperture and through which the cam carrying sleeve passes, a button carried by the rod and having a recess in one face, into which both of the sleeves extend, the cam carrying sleeve abutting against the button to cause the rod and shaft to move in unison when shifted endwise, and permit rotation of the rod independently thereof, and spring pressed detents carried 105 in the lower end of the sleeve engaging with recesses in the button to position and yieldingly hold the button in different rotative positions with respect to the sleeve.
40. In a lens cutting machine, a frame 105 having a vertically extending aperture and a bearing face upon the frame at the upper end of the aperture, a hollow stem adjustably threaded into the upper end of said aperture and having stepped shoulders upon its upper end, a gear rotatably carried by the stem and held against the upper bearing surface of the frame by the smaller shoulder, a lens support having an elongated slot in its lower face through which the portion of the 110 stem between the shoulders passes, said support being held against the gear by the larger shoulder, but slidable across the same by means of the slot, a sleeve slidable vertically in said stem, a plurality of cams carried by 115 the upper end of the sleeve and co-acting with the support to selectively control its path of movement, dependent upon the extent of vertical adjustment, means including a gear member meshing with said gear for 120 rotating the gear and support, a rod rotatably carried by the stem, means carried by the upper end of the rod for displacing the cams upon the sleeve to various extents eccentrically to the axis of rotation of the gear, a hollow sleeve rigidly carried by the frame at the lower end of the aperture and through which the cam carrying sleeve passes, and a button carried by the rod and having a recess in one face, into which both of the sleeves extend, the cam carrying sleeve abutting against the button to cause the rod and shaft to move in unison when shifted endwise, and permit rotation of the rod independently thereof.

36. In a lens cutting machine, a frame 65 having a vertically extending aperture and a bearing face upon the frame at the upper end of the aperture, a hollow stem adjustably threaded into the upper end of said aperture, and having stepped shoulders upon its upper end, a gear rotatably carried by the stem and held against the upper bearing surface of the frame by the smaller shoulder, a lens support having an elongated slot in its lower face through which the portion of the stem 70 between the shoulders passes, said support being held against the gear by the larger shoulder, but slidable across the same by means of the slot, a sleeve slidable vertically in said stem, a plurality of cams carried by 75 the upper end of the sleeve and co-acting with the support to selectively control its path of movement, dependent upon the extent of vertical adjustment, means including a gear member meshing with said gear for 80 rotating the gear and support, a rod rotatably carried by the stem, means carried by the upper end of the rod for displacing the cams upon the sleeve to various extents eccentrically to the axis of rotation of the gear, a hollow sleeve rigidly carried by the frame at the lower end of the aperture and through which the cam carrying sleeve passes, a button carried by the rod and having a recess in one face, into which both of the sleeves extend, the cam carrying sleeve abutting against the button to cause the rod and shaft to move in unison when shifted endwise, and permit rotation of the rod independently thereof, and spring pressed detents carried 85 in the lower end of the sleeve engaging with recesses in the button to position and yieldingly hold the button in different rotative positions with respect to the sleeve.
37. In a lens cutting machine, a frame 95 having a vertically extending aperture and a bearing face upon the frame at the upper end of the aperture, a hollow stem adjustably threaded into the upper end of said aperture and having stepped shoulders upon its upper end, a gear rotatably carried by the stem and held against the upper bearing surface of the frame by the smaller shoulder, a lens support having an elongated slot in its lower face through which the portion of the stem 100 between the shoulders passes, said support being held against the gear by the larger shoulder, but slidable across the same by means of the slot, a sleeve slidable vertically in said stem, a plurality of cams carried by 105 the upper end of the sleeve and co-acting with the support to selectively control its path of movement, dependent upon the extent of vertical adjustment, means including a gear member meshing with said gear for 110 rotating the gear and support, a rod rotatably carried by the stem, means carried by the upper end of the rod for displacing the cams upon the sleeve to various extents eccentrically to the axis of rotation of the gear, a hollow sleeve rigidly carried by the frame at the lower end of the aperture and through which the cam carrying sleeve passes, and a button carried by the rod and having a recess in one face, into which both of the sleeves extend, the cam carrying sleeve abutting against the button to cause the rod and shaft to move in unison when shifted endwise, and permit rotation of the rod independently thereof.

- cams upon the sleeve to various extents eccentrically to the axis of rotation of the gear, an operating button upon the lower end of the rod for rotating the same to vary the eccentricity of the cams and abutting the sleeve to shift the same to change the cams in control of the support when the button and rod are shifting endwise, said sleeve being adjustable in length to take up lost motion between the parts carried at the opposite ends of the rod and the sleeve.
38. In a lens cutting machine, a frame having an aperture, means for rotatably carrying a lens on said frame, a cutter operating member adjustably threaded into said aperture, and having an extension also in said aperture, said extension being threaded in a direction opposite from the threads between the member and frame, a sleeve into which the extension is adjustably threaded and which is slidably and non-rotatably carried in said aperture, whereby rotation of the member to move it into or out of the aperture will produce an amplified longitudinal movement of the member, and lens cutting means carried by the sleeve.
39. In a lens cutting machine, a frame having an aperture, means for rotatably carrying a lens on said frame, an operating member adjustably threaded into said aperture, and having an extension also in said aperture, said extension being threaded in a direction opposite from the threads between the member and frame, a sleeve into which the extension is adjustably threaded and which is slidably and non-rotatably carried in said aperture, whereby rotation of the member to move it into or out of the aperture will produce an amplified longitudinal movement of the sleeve in the same direction as the longitudinal movement of the member, and a lens cutter device rotatably carried by the outer end of the sleeve, and a rod rigidly carried by the cutter device and extending through the sleeve, extension and member and having a rotative bearing with the member adjacent its outer end.
40. In a lens cutting machine, a frame having an aperture, means for rotatably carrying a lens on said frame, an operating member adjustably threaded into said aperture, and having an extension also in said aperture, said extension being threaded in a direction opposite from the threads between the member and frame, a sleeve into which the extension is adjustably threaded and which is slidably and non-rotatably carried in said aperture, whereby rotation of the member to move it into or out of the aperture will produce an amplified longitudinal movement of the sleeve in the same direction as the longitudinal movement of the member, and lens cutting means carried by the sleeve, said member having a spirally arranged scale thereon for co-operation with the frame to indicate the displacement of the cutter from the center of the lens.
41. In a lens cutting machine, a frame, means for rotatably carrying a lens on said frame, an operating member having two sets of threads thereon of which one is a right hand set and the other is a left hand set, said frame having threads with which one of said sets of threads engages to permit adjustment of the member upon the frame, lens cutting means slidably and non-rotatably carried by said frame and having threads in engagement with the other set of threads for adjustment thereon whereby rotation of the member will produce an amplified movement of the lens cutting means in the same direction as that of the member due to its threaded engagement with the frame.
42. In a lens cutting machine, a frame, means for rotatably carrying a lens on said frame, an operating member spirally adjustable onto and out of said frame, and lens cutting means shiftable by said member, said member having a spirally arranged scale thereon for co-operation with a graduation on said frame to directly indicate the displacement of the cutter from the center of a lens.
43. In a lens cutting machine, a frame, means for rotatably carrying a lens on said frame, lens cutting means adjustable on said frame to bring the cutter toward or from the center of a lens, and shifting means adjustably carried by the frame and having a connection with said cutting means for producing amplified movements of the lens cutting means in one direction or the other as desired.
44. In a lens cutting machine, a frame, means for rotatably carrying a lens on said frame, an operating member spirally adjustable on said frame, and lens cutting means shiftable on said member and movable into and out of the frame at a rate different from that of the member, said frame and member having co-operating scale indications to indicate the displacement of the cutter from the center of a lens.
45. In a lens cutting machine, a frame having an aperture, an operating member adjustably threaded into one end of said aperture and having a separate set of threads, and a cutter carrier slidably and non-rotatably supported in the other end of said aperture and having threaded engagement with the said separate set of threads.
46. In a lens cutting machine, a frame having an aperture, an operating member adjustably threaded into one end of said aperture and having a separate set of threads, and a cutter carrier slidably and non-rotatably supported in the other end of said aperture and having threaded engagement with the said separate set of threads, said member having a spirally arranged scale thereon for co-operation with the frame.

scale for indicating by reference to a fixed point on the frame, the displacement of the cutter from the center of a lens.

47. In a lens cutting machine, a frame having an aperture, an operating member adjustably threaded into one end of said aperture and having a separate set of oppositely directed threads, and a cutter carrier slidably and non-rotatably supported in the other end of said aperture and having threaded engagement with the said separate set of threads.

48. In a lens cutting machine, a frame having an aperture, an operating member adjustably threaded into one end of said aperture and having a separate set of oppositely directed threads, and a cutter carrier slidably and non-rotatably supported in the other end of said aperture and having threaded engagement with the said separate set of threads, said member having a spirally arranged scale for indicating by reference to a fixed point on the frame, the displacement of the cutter from the center of a lens.

49. In a lens cutting machine, a frame, a lens support, means carried by the frame for giving said support a combined rotary and lateral movement, a lever carried by the frame, a cutter rotatably carried by the lever, an arm having a slot therein carried by the cutter, a forked member pivoted to the lever and having a pin engaging in said slot in said arm, said member embracing said lens support whereby movement of the latter will oscillate the forked member and through the pin and arm oscillate the cutter to always present the cutter in the same relative position to the cutting line of the lens automatically during the combined movement of the support.

50. In a lens cutting machine, a support-

ing frame, a lens table mounted for movement on said frame, means for imparting movement to said lens table, a cutter carried by the frame, and a one way clutch between 45 said means and frame for limiting relative movement between the cutter and lens to one direction.

51. In a lens cutting machine, a frame, a lens supporting element, means for supporting the element for both lateral and rotary movement and for imparting rotary movement thereto, a pair of guides carried by said element, a cam element for guiding the rotary and lateral movement and having 55 cam surfaces of different characteristics in different transverse planes, and means for shifting the cam element endwise to bring any selected one of the cam surfaces into 60 cooperative engagement with the guides and control the rotary and lateral movement of the lens supporting element.

52. In a lens cutting machine, a frame, a lens supporting element, means for supporting the element for both lateral and rotary 65 movement and for imparting rotary movement thereto, a pair of guides carried by said element, a cam element for guiding the rotary and lateral movement and having cam surfaces of different characteristics in 70 different transverse planes, means for shifting the cam element endwise to bring any selected one of the cam surfaces into cooperative engagement with the guides, and means for shifting said cam element laterally 75 to additionally control the lateral movement of the supporting element by the extent of the eccentricity of the cam element with respect to the supporting means.

In witness whereof, I hereunto subscribe 80 my signature.

OTTO WITTEL.
